NUMBERING MACHINE

Ernest Persson, New York, N. Y., assignor to The International Postal Supply Company, Brooklyn, N. Y., a corporation of New York

Application March 25, 1946, Serial No. 656,883

15 Claims. (Cl. 101—76)

1

This invention relates to a numbering machine and more particularly to a machine for printing numbers on checks, tickets, or the like, at high speed.

A feature of the invention is the provision of a simple, rugged, consecutive numbering machine which may be used for a variety of purposes such as printing consecutively numbered tickets in a continuous strip, or for numbering discrete objects such as checks or the like. When checks or separate objects of this kind are to be numbered, the numbering machine may be included in a suitable endorsing die preferably operated cyclically in start-stop fashion, so that an imprint is made uniformly in a predetermined position on the respective checks or objects.

Other features will be found in the following description given with the aid of the accompanying drawings, of which

Fig. 1 is an elevational view of a numbering machine according to a preferred embodiment of the invention;

Fig. 2 is a plan view;

Fig. 3 is a perspective view of a feed pawl assembly and part of the actuating mechanism therefor;

Fig. 4 is a section taken through 4—4 of Fig. 1;

Fig. 5 is a section taken through 5—5 of Fig. 1;

Fig. 6 is a section taken through 6—6 of Fig. 2; and

Fig. 7 shows a group of number wheels arranged in order, the units wheel being at the top of the figure.

The invention is shown in Figs. 1 and 2 together with a portion of a machine for endorsing checks or the like to illustrate the operation of a preferred embodiment thereof. Various details of a complete endorsing machine, such as the base, shaft bearings, motor, and parts of the feeding mechanism have been omitted as they form no part of the present invention.

Referring to Fig. 1, a driving motor, not shown, drives a gear 40 on a vertical shaft 41. Secured to shaft 41 is a clutch cup 42 which drives through suitable frictional connections, not shown, a driven member 43 formed with a hollow concentric portion within which is detachably disposed an end portion of a spindle 44. The driven member 43 is formed with a pair of oppositely disposed recesses into which fit splines 45 formed on spindle 44. The clutch cup 42 rotates constantly as long as power is supplied, but the driven member 43 is normally at rest, being restrained from rotation by a trip mechanism, to be described, which when operated releases for one revolution driven member 43 and a printing die 31 coupled therewith.

The printing die 31 which cooperates in the known manner with a rotary platen 30 is of the general shape of a hollow cylinder or drum, on the outer surface of which suitable type or other

2

indicia to be printed is disposed. The die is formed into two separable sections as will be described. The upper section of the die has a shaft 46 projecting upwardly therefrom disposed concentrically with respect to spindle 44. Shaft 46 turns in a bearing 47 in the bracket 48 attached to upright 32 supported by the base of the machine, not shown.

Referring to Fig. 6, immediately under bracket 48, shaft 46 has a concentric shoulder 49 formed thereon of substantially greater diameter than the shaft. A roller support 50 provided with an arm 51 has an opening therein which fits over shoulder 49. A roller 55 disposed in recess 56 in arm 51, turns on the shank of a long screw 57 which extends through the arm 51, and through flange 58 integral with the top portion 52 of the printing die, the screw being threaded into a suitable hole in the part 51, thereby securing the roller 55 and roller support 50 to the assembly.

The die is stopped invariably in the same angular position each time it is released by means of a roller 60, Fig. 2, pivoted at one end of lever 61 which turns on pivot 62 attached to the underside of bracket 48. The lever is operated by a check actuated trip mechanism which will be described in detail below. Roller 60 is normally positioned in the path of roller 55 so as to stop the rotary movement of the die. When the lever 61 is actuated by the trip mechanism, the lever is turned as shown in Fig. 2 to move the roller 60 out of the path of roller 55 permitting the die to turn. In the normal position of rest when the die is in stop position, the axes of rollers 55 and 60, as well as that of lever 61, are disposed along a straight line, lever 61 then resting against a stop pin 63. Only a slight amount of pressure is necessary on lever 61 to upset this alignment, and once this is done, the torque exerted through the clutch on the die 31 and communicated thereby to arm 51 and roller 55 turns roller 60 and lever 61 to one side until the roller 55 and die are free, whereupon lever 61 snaps back against stop 63 bringing roller 55 again into position to stop the die at the end of the cycle.

A spring post 65 is adjustably secured in an opening in bracket 48 by a clamping screw 66. A spring 67 is fastened between a turned over end portion of the spring post and lever 61 for the purpose of resiliently holding the lever against its stop pin 63. The tension of the spring is adjustable as required by clamping the spring post by screw 66 in the desired position.

One end of a trip tongue link 70 is pivotally connected to the underside and near the end of the opposite arm of lever 61 by a screw 71, while the opposite end of the link 70 is pivotally connected by stud 72 to the trip tongue 73, the latter being a lever having as a fulcrum a stud 74 supported by the arm 75 of a lever 76. The latter lever has offset arms, a second and upper arm 77

thereof being disposed adjacent the lower surface of bracket 48. The arms are connected by a hollow shank 78 through which extends a headed pivot rod 79 which projects into an opening in a block 80 fastened to the side of bracket 48. The rod 79 is held in place by screws 81.

A spring 85 fastened at one end to arm 77 of lever 76 and at the other to bracket 48 tends to hold arm 77 against a stop 86 formed in block 80. When the lever rests against the stop, the trip tongue pivot 74 is slightly below the pivot 79 of lever 76 as shown in Fig. 2. With this arrangement checks or other matter passing through the machine will actuate trip tongue lever 73 only about its pivot 74 thus releasing the die for rotation. However, pressure on the end of lever 73 in any other direction than toward the left of the drawing, as shown by the arrow in Fig. 2 will rock lever 75 about its fulcrum and this movement will be taken up as rotary displacements of link 70 about its pivots 71 and 72 without imparting the thrust to lever 61 necessary to rock the same to release the die 31. The trip tongue may be pushed back clear of the guideway when desired without causing undesired actuation of the die and the numbering mechanism therein. Guard members 87 and 88 attached to bracket 48 are disposed respectively above and below trip lever 73 to protect the same against unwanted operations and to serve in cooperation with a guide plate 53 disposed in spaced relation thereto to guide the matter being printed or endorsed.

The upper part of die 31 comprises a disc-shaped member indicated generally by reference character 52 attached concentrically to shaft 46. A groove 54 formed part way around the member where it is enlarged into a deep slot or recess 91, defines the upper flange portion 58 and a lower portion 59 of member 52, the lower and upper surfaces of these members being respectively the upper and lower walls of recess 91. The lateral dimensions of the recess are shown by the unshaded portion of Fig. 5, where the shaded portion 90 is the part of the end piece by which flange 58 is connected to the lower part 59.

A lever 92 which actuates the consecutive numbering mechanism is supported in the recess 91 on a pivot 93 eccentrically disposed with respect to the axis of die 31. An end 94 of the lever projects beyond the periphery of the endpiece 52 and engages a pin or stop 95 depending from bracket 48, Fig. 1, with each rotation of the die thereby rocking the lever on its pivot. Since the pivot 93 is off center with respect to the axis of the die, it will readily disengage itself from pin 95 as the die continues to rotate. The opposite end 96 of the lever is bifurcated, and between its two arms is a pin 97 fixed to a plate 98 disposed immediately underneath the lower part 59 of the end piece and extending upward through a rather large, approximately centrally located opening 83 in the part 59 communicating with recess 91.

Plate 98 is a part of a cage-like arrangement carrying feed pawls, which is oscillated by lever 92 about an axis, with each revolution of die 31.

Plate 98 is attached in spaced relation to a similar plate 99 by means of shoulder pins 100 and 101, Figs. 3 and 5, the latter serving as a shaft for an assembly of number wheel actuating pawls fixed in spaced relation to a tubular member 102 which is free to turn on shaft 101.

A shaft 106 having a plurality of number wheels thereon extends through plates 98 and 99 and forms the axis about which these plates are oscillated. The plates turn respectively between

shoulders at opposite ends of shaft 106 and the upper and lower end walls of the space within the die, the upper end of shaft 106 turning in a bearing in the upper end piece 59, and the lower end of the shaft being disposed in a bearing in the base 107 of the die which is formed integrally with the cylindrical wall 108 of the die. Wall 108 has a longitudinal opening in the side thereof through which project the portion of the number wheels to be presently used for a printing operation. The upper and lower parts of the die, including the cylindrical wall, are fastened together by suitable dowel pins and screws, not shown.

In Fig. 7, four number wheels 111, 112, 113 and 114 are shown arranged in order, the top wheel 111 being the units wheel and the lowermost wheel 114, the thousands wheel. Each number wheel has a ratchet wheel attached thereto which is actuated by a pawl of the actuating pawl assembly. Pawl 115 actuates ratchet wheel 116 of the unit number wheel 111; pawl 117 the ratchet wheel 118 of the tens wheel 112; pawl 119 the ratchet wheel 120 of the hundreds wheel 113; and pawl 121 actuates the ratchet wheel 122 of the thousands wheel 114. The interior of die 31 is preferably large enough to permit the use of a greater number of number wheels, if numbering beyond the capacity of the four wheels shown is required. Furthermore, one or more manually movable wheels carrying various indicia, such as for dating purposes, or the like, can be mounted on shaft 106, space being provided for this purpose below the number wheels.

With each revolution of die 31, as already described, lever 94 rocks the cage arrangement about shaft 106. Lever 94 and the cage are restored to their normal position by a spring 123, Figs. 4 and 5, disposed in a recess in the under side of end piece 59, the spring having one end attached to a spring post on the upper surface of plate 94 and the other attached to a hook 126, attached to end piece 59. The rocking movement imparted by the initial movement of lever 94 withdraws the pawls 111-114 so that they are in position to drop behind the next tooth of the associated ratchet wheel. The spring 123 thereafter is effective to restore the lever 94 and cage to normal thus advancing the position of the wheels engaged by the pawls by one tooth. As will be explained, lever 94 is usually effective to advance only the units number wheel 111, the other wheels being advanced only when a carry-over operation is necessary.

In order to provide for carry-over, the noses of actuating pawls 115-121 progressively differ in length, pawl 115 for the units wheel having the longest nose, while pawl 121 for the thousands wheel has the shortest nose. Since all of these pawls are fixed to the tubular member 102, all are displaced away from their ratchets except pawl 115 due to the long nose of the latter, except when a carry over occurs when one or more of the other pawls will be effective to operate their ratchets, the arrangement operating as follows: When any of the wheels is in position to print a "9," the next operation of lever 94 effective to advance that wheel will turn the wheel to "0" position. In the latter position, all of the wheels except the thousands wheel have progressively greater than normal depressions between their particular pairs of ratchet teeth. From Fig. 7, it may be seen that the spaces between all teeth of the thousands wheel are uniform. Wheel 120 has a slight but noticeable depression 130 for the

zero position, while the corresponding positions of wheels 112 and 111 have progressively deeper depressions 131 and 132.

The pawls of the actuating pawl assembly may be urged toward their ratchets by any suitable means such as by a spring 138 attached between one of the pawls and pin 109. With each operation of lever 94, the units wheel advances one tooth. When pawl 115 drops into the zero depression, the pawl assembly, due to the depression, will turn through a greater angle about pawl shaft 101 in a clockwise direction which will be sufficient to permit the pawl 117 of the next higher wheel to be lowered enough to engage the next ratchet tooth thereof, and on the return movement of the cage assembly caused by spring 123, both the units wheel 111 and the tens wheel 112 will be advanced one step. With the next following operation, pawl 115 will be riding on the higher spot between the next ratchet teeth and also those following, and the remaining pawls remain out of engagement with the associated ratchets until wheel 111 again reaches the zero position and the carry over occurs again advancing wheel 112 another step.

When wheel 112 is at the zero position, and pawl 115 of wheel 111 drops into the deep depression, the pawl assembly will turn through a still greater angle about the common pawl shaft 101 in a clockwise direction permitting pawl 119 to engage and advance the hundredths wheel 113 one tooth. In the same manner, when the space 130 of wheel 113 is under pawl 119, all pawls will turn sufficiently for pawl 121 of the highest order wheel 114 to drop behind a tooth and advance the ratchet 122 one step. The wheels are shown lined up in Fig. 7 for the latter operation, the first three wheels being each positioned to print "9." With the following retraction of the pawl assembly, all three pawls will drop into their zero position notches, and when they are advanced by spring 123 all four wheels will advance one step, the first three wheels being now positioned to print zero, while wheel 114 will be positioned to print the particular character at which it happens to be positioned.

The ratchets have individual retaining pawls 135 for holding the number wheels in position. These pawls are free to turn on a rod 136 on which they are held in spaced relation by spacing sleeves 137. Each pawl 135 is pressed toward its ratchet by a spring 138 attached to a vertical rod 139 held in openings formed in opposite ends 59 and 107 of die 31.

When used with a check endorsing machine of the type referred to, the invention operates as follows: Assume that checks or other objects are fed one at a time by any suitable means through the guideway formed by guide plate 53 and members 37 and 38, a pair of feed rollers being indicated by dotted lines in the plan view Fig. 2 as a part of a mechanism for this purpose. There is a space between roller 38 and the surface of the die when in position of rest. Through this space the checks are fed and the forward edge thereof engages trip lever 73 and rocks the same clear of the guideway thereby releasing the die which rotates one revolution rolling the inked endorsing or printing indicia thereon as the check passes through the guideway, the numbering wheels being effective to consecutively number the checks as they pass. With each revolution of the die, the number wheels are advanced by one unit as described. Any suitable device, such as an ink-

ing roller, not shown, may be used to ink the die. In order to insure accurate operation, the numbering mechanism should be cleaned frequently. The detachable coupling by which shaft 44 is connected with the clutch permits the die to be easily removed from the machine for cleaning.

While but one illustrative embodiment of the invention has been herein shown and described, it will be understood that numerous details of the arrangement may be altered without departing from the spirit of the invention as defined by the following claims.

What is claimed is:

1. In a numbering machine, a member supported for uni-directional rotation about an axis, a shaft supported by the member in parallel off-set relation to said axis, an assembly of number wheels disposed for rotation on the shaft, a pair of plates respectively disposed on the shaft on opposite sides of the number wheel assembly, pawl means for actuating the number wheels pivotally supported by the plates, and means for rocking the plates on the shaft and thereby causing the pawl means to actuate the number wheels which comprises a lever supported by the member operatively connected to the plates, and a stop disposed in the path of the lever for engaging and operating the same with each revolution of the member.

2. In a numbering machine, a printing member supported for uni-directional rotation about an axis, a shaft supported by the member in parallel off-set relation to said axis, an assembly of numbering wheels each provided with a ratchet disposed for rotation on the shaft, a lever pivotally supported by the member having a slot formed in one arm, a stop pin disposed in the path of a second arm of the lever effective to trip the same with each revolution of the member, a pair of plates respectively disposed on the shaft on opposite sides of the numbering wheels, means for actuating the plates by the lever comprising a member fixed to the plates and extending into the slot in the lever and pawl means supported alongside the numbering wheels by the plates effective on the actuation of the plates to advance the number wheels.

3. In an endorsing machine having a hollow die member generally cylindrical in shape with matter to be printed disposed on the surface thereof and formed with a longitudinal opening in the side thereof, the die member being supported for rotation by shafts coaxially fixed at the ends thereof, the improvement which comprises means for consecutively numbering the endorsements as printed which comprises a shaft supported within the member adjacent said opening in parallel off-set relation to the axis of the die member, an assembly of number wheels disposed for rotation on the shaft and in register with the matter to be printed on the surface of the die member, a lever supported by the die member, a stop pin disposed in the path of the lever effective to trip the same with each revolution of the die member, pawl means for advancing the number wheels, and actuating means for the pawl means comprising a pin and slot mechanism operatively connecting the pawl means with one arm of the lever.

4. In an endorsing machine having a hollow die member generally cylindrical in shape with matter to be printed disposed on the surface thereof and formed with a longitudinal opening in the side thereof, the die member being supported for rotation by shafts coaxially disposed

at the ends thereof, the improvement which comprises means for consecutively numbering the endorsements as printed which comprises a shaft supported within the member adjacent said opening in parallel off-set relation to the axis of the die member, an assembly of number wheels each provided with a ratchet disposed for rotation on the shaft, a lever supported by the member having a slot formed in one arm, a stop pin disposed in the path of the opposite arm of the lever effective to trip the same with each revolution of the member, pawl means for the respective ratchets, a pin disposed in the slot operatively connected to the pawl means effective to actuate the pawl means to advance the number wheels with each operation of the lever by the stop pin, and a rotary platen cooperating with the die member.

5. In an endorsing machine having a hollow die member generally cylindrical in shape with matter to be printed disposed on the surface thereof and formed with a longitudinal opening in the side thereof, the die member being supported for rotation by shafts coaxially disposed at the ends thereof, means for consecutively numbering the endorsements as printed which comprises a shaft supported within the member adjacent said opening in parallel off-set relation to the axis of the die member, an assembly of number wheels each provided with a ratchet disposed for rotation on the shaft, a lever pivotally supported by the member, a stop pin disposed in the path of one arm of the lever effective to trip the same with each revolution of the member, a pair of plates respectively disposed on the shaft on opposite sides of the number wheels, actuating means for the plates comprising a slideable connection between a second arm of the lever and the plates and pawl means supported alongside the number wheels by the plates effective on the actuation of the plates to advance the number wheels.

6. In an endorsing machine having a hollow die member generally cylindrical in shape with matter to be printed disposed on the surface thereof, and formed with a longitudinal opening in the side thereof, the die member being supported to turn about its axis, means for consecutively numbering the endorsements as printed which comprises a shaft supported within the member adjacent said opening in parallel off-set relation to the axis of the die member, an assembly of number wheels each provided with a ratchet disposed for rotation on the shaft, a lever pivotally supported by the member, a stop pin disposed in the path of the lever effective to trip the same with each revolution of the member, a pair of plates actuated by the lever respectively disposed on the shaft on opposite sides of the number wheels, pawl means supported alongside the number wheels by the plates effective on the actuation of the plates to advance the number wheels, and a spring attached to the lever for restoring the same to a position of rest and thereby effecting a corresponding displacement of the plates and also the pawls.

7. In a numbering machine, a member supported for uni-directional rotation about an axis, a shaft supported by the member in parallel off-set relation to said axis, an assembly of number wheels disposed for rotation on the shaft, a pair of plates respectively disposed on the shaft on opposite sides of the number wheel assembly, pawl means for actuating the number wheels pivotally supported by the plates, means for

rocking the plates on the shaft and thereby causing the pawl means to actuate the number wheels which comprises a lever supported by the member operatively connected to the plates, a stop disposed in the path of the lever for engaging and operating the same with each revolution of the member, and a start stop mechanism controlling the rotation of the member effective to initiate the successive tripping operations of the lever.

8. In an endorsing machine having a hollow die member generally cylindrical in shape with matter to be printed disposed on the surface thereof and formed with a longitudinal opening in the side thereof, the die member being supported for rotation by shafts coaxially disposed at the ends thereof, means for consecutively numbering the endorsements as printed which comprises a shaft supported within the member adjacent said opening in parallel off-set relation to the axis of the die member, an assembly of number wheels disposed for rotation on the shaft and in register with the matter to be printed on the surface of the die member, a lever supported by the die member, a stop pin disposed in the path of one arm of the lever effective to trip the same with each revolution of the die member, pawl means for operating the number wheels, a rockable support for the pawl means, means including a pin and slot mechanism connecting the support with a second arm of the lever to effect the operation of the pawl means to advance the number wheels with each tripping operation of the lever, a rotary platen cooperating with the die member, and a start-stop mechanism controlling the rotation of the die member effective to initiate the respective operations of the number wheels.

9. In an endorsing machine having a hollow die member generally cylindrical in shape with matter to be printed disposed on the surface thereof and formed with a longitudinal opening in the side thereof, the die member being supported for rotation by shafts coaxially disposed at the ends thereof, means for consecutively numbering the endorsements as printed which comprises a shaft supported within the member adjacent said opening in parallel off-set relation to the axis of the die member, an assembly of number wheels each provided with a ratchet disposed for rotation on the shaft, a lever supported by the member, a stop pin disposed in the path of one arm of the lever effective to trip the same with each revolution of the member, pawl means for the respective ratchets, a rockable support for the pawl means, means connecting a second arm of the lever to the support effective to rock the same and actuate the pawl means to operate the number wheels with each operation of the lever by the stop pin, a rotary platen cooperating with the die member, and a start-stop mechanism controlling the rotation of the die member effective to initiate the respective operations of the number wheels.

10. In an endorsing machine having a hollow die member generally cylindrical in shape with matter to be printed disposed on the surface thereof, and formed with a longitudinal opening in the side thereof, the die member being supported to turn about its axis, means for consecutively numbering the endorsements as printed which comprises a shaft supported within the die member adjacent said opening in parallel off-set relation to the axis of the die member, an assembly of number wheels each provided

with a ratchet disposed for rotation on the shaft, a lever pivotally supported by the die member eccentrically with respect to the axis thereof, a stop pin disposed in the path of the lever effective to trip the same with each revolution of the die member, a pair of plates actuated by the lever respectively disposed on the shaft on opposite sides of the numbering wheel assembly, pawl means supported alongside the numbering wheels by the plates effective on the actuation of the plates to advance the number wheels, a spring attached to the lever for restoring the same to a position of rest and thereby effecting a corresponding displacement of the plates and also the pawls, and a start-stop mechanism controlling the rotation of the die member effective to initiate the respective operations of the number wheels.

11. In a numbering mechanism adapted to be used with check endorsing apparatus and the like, a rotatable hollow cylindrical member carrying check endorsing indicia on its surface and formed with a longitudinal slot, a set of numbering wheels for consecutively numbering the endorsements supported within the cylindrical member adjacent to the slot and partially projecting through the slot, a pair of plates pivotally supported respectively on opposite sides of the set of number wheels, a set of number wheel actuating pawls supported between the plates, a member formed with a recess in its edge fixed to the cylindrical member adjacent one of the plates, a pin fixed to the latter plate extending into the recess, a lever pivotally mounted in the recess having a first arm projecting beyond the surface of the cylindrical member, and a second arm engaging the pin, and a stationary pin disposed in the path of the first lever arm for engaging and rocking the same together with the plates to cause operation of the number wheels by the actuating pawls.

12. In a numbering mechanism adapted to be used with check endorsing apparatus and the like, a rotatable hollow cylindrical member carrying check endorsing indicia on its surface formed with a longitudinal slot, a shaft supported within the cylindrical member, a pair of plates secured in spaced relation to each other supported for rocking movement on the shaft, a lever pivoted to one end of the cylindrical member having one arm pivotally connected to the plates and another arm projecting beyond the surface of the cylindrical member, a fixed stop disposed in the path of the latter arm effective when engaged thereby to rock the lever which in turn rocks the plates, a set of number wheels mounted on the shaft between the plates disposed to partially project outwardly through the slot and pawl means carried adjacent the number wheels by the plates effective on the rocking thereof to actuate the set of number wheels.

13. In a numbering mechanism adapted to be used with check endorsing apparatus and the like, a rotatable hollow cylindrical member formed with a longitudinal opening, a shaft supported within the cylindrical member, a pair of plates secured in spaced relation to each other supported for rocking movement on the shaft, a lever pivoted to one end of the cylindrical member having one arm formed with a slot and another arm projecting beyond the surface of the drum, a pin disposed in the slot fixed to one of the plates for communicating rocking movement of the lever to the plates, a set of number wheels mounted on the

shaft between the plates disposed to project through the longitudinal opening slightly beyond the outer surface of the cylindrical member for printing purposes, and pawl means disposed between the plates and pivotally supported thereby for actuating the number wheels on the rocking of the plates.

14. In a numbering mechanism adapted to be used with check endorsing apparatus and the like, a rotatable bi-partite printing die assembly comprising a hollow cylindrical member closed at one end and formed with a longitudinal opening and a relatively thick disc having a slot in its edge secured to and forming a closure for the opposite end of the cylindrical member, a shaft supported within the cylindrical member between the ends thereof, a pair of plates secured in spaced relation to each other supported for rocking movement on the shaft, a lever pivotally supported in the slot having one arm pivotally connected to the plates and another arm projecting beyond the surface of the cylindrical member, a fixed stop disposed in the path of the latter arm effective when engaged thereby to rock the lever which in turn rocks the plates, a set of number wheels mounted on the shaft between the plates disposed to partially project outwardly through the longitudinal opening, and pawl means pivotally supported between the plates effective on the rocking thereof to actuate the set of number wheels.

15. In a numbering mechanism adapted to be used with check endorsing apparatus and the like, a rotatable bi-partite printing die assembly comprising a hollow cylindrical member closed at one end and formed with a longitudinal opening, and a relatively thick disc having a recess in its edge secured to and forming a closure for the opposite end of the cylindrical member, a shaft supported within the cylindrical member by the respective ends thereof, a pair of plates secured in spaced relation to each other supported for rocking movement on the shaft, an actuating lever for rocking the plates pivotally supported in the recess having one arm formed with a slot and a second arm projecting beyond the edge of the disc, a pin disposed in the slot fixed to one of the plates, a set of number wheels mounted on the shaft between the plates disposed to project through the longitudinal opening slightly beyond the outer surface of the cylindrical member for printing purposes, and pawl means disposed between the plates and pivotally supported thereby for actuating the number wheels on the rocking of the plates.
